CLAIM

The ornamental design for a farm motif slot machine, as shown and described.

DESCRIPTION

FIG. 1 is a front view of a farm motif slot machine, showing my new design;
FIG. 2 is a rear view thereof;
FIG. 3 is a left side view thereof;
FIG. 4 is a right side view thereof;
FIG. 5 is a top view thereof;
FIG. 6 is a bottom view thereof; and,
FIG. 7 is a front perspective view thereof.
The broken lines are for the purpose of illustrating environmental structure and form no part of the claimed design.
